RAIL UNIT FOR MOTOR VEHICLES

Dave F. Gebhart, 578 Lincoln Way, Auburn, Calif.

Filed Apr. 18, 1963, Ser. No. 74,503

Term of patent 14 years

(Cl. D14—6)

Fig. 1

Fig. 2

Fig. 3

Fig. 4

FIG. 1 is a rear perspective view of a rail unit for motor vehicles, showing my design;

FIG. 2 is a fragmentary side elevational view thereof;

FIG. 3 is a fragmentary top plan view thereof; and

FIG. 4 is a fragmentary rear elevational view thereof.

The rail unit shown in broken lines in FIG. 1 and the motor vehicle shown in broken lines are included for illustrative purposes only.

I claim:

The ornamental design for a rail unit for motor vehicles, as shown and described.
